(54) **SHAVING LEATHER**

(76) Inventor: **Herkimer Johnson**

W. Beckimer & Johnson of Brooklyn Connecticut
Letters Patent.

The Schedule referred to in these Letters Patent and making part of the same containing a description in the words of the record of the said Wm. Beckimer & Johnson himself of his improvement in the machine for shaving and smoothing all kind of tanned leather."

To all to whom these presents shall come. Be it known that Wm. Beckimer & Johnson of the Town of Brooklyn in the County of Windham and State of Connecticut have invented a new and useful machine for shaving and smoothing leather and that the following is a full and exact description thereof viz a machine for shaving and smoothing all kinds of tanned leather with one or more knives, each side of the leather or skin can be shaved off of one thickness or raised to any desirable thickness. The machine may be raised to any size according to the width of the leather to be shaved and smoothed. The length of the knives may be varied on the same shaft.

The knives are placed over a wheel in the form of a cylinder and for best leather or for economy use the wheel is made of wood and consists of five iron wheels six inches diameter placed on an iron shaft about four feet in length and two and a half inches diameter at equal distances from each other. On these wheels would be placed nine knives two inches apart and one foot and a half long in an angular direction across the wheel by first securing flat knives of iron one inch in width and half an inch or more across the wheel in the same length and shape of the iron. Then shave the knives on their

ground to an edge on the under side. Most knives are made use of in shaving rough leather for the purpose of turning the leather for shaving the leather in a direction and for the purpose of shaving to any desirable thickness, the knives must be as long as the skins are wide. The machine is enclosed in a frame about four feet

square with two of the top posts running over the corner posts about one foot. At the frame is a second, perpendicular post two feet from the corner post and inserted into the top and lower

and lower joint, . . . I then have a joint three feet in length, one end into ^{the} second post with a mortise through it two feet from the second post and the corner post flattened. It is to slide up and down and raised or lowered by means of stones placed on the top of the sliding joint. The cylinder of knives is placed with the top of the frame one foot from the corner post, and in the centre of the cylinder and on the sliding joint is placed a iron roller about three inches diameter and about four feet long to drive the leather through directly under the cylinder of knives. And I place two smaller rollers of iron wire to the large one and the holes are to be equal to the large one and the other one placed on the top of the large one for the purpose of driving the leather more directly under the knives and over the large roller. By turning the cylinder the leather is drawn through the machine and shaved. The cylinder is turned by a pulley or pinion four inches diameter placed on the end of the shaft of the cylinder driven by a wheel thirty inches diameter placed on the end of a shaft one inch diameter and four feet in length with a belt from one to the other on which is placed a crank. On the other end of the inch shaft is placed a pulley or pinion two inches diameter for the purpose of turning the iron rollers under the cylinder of knives by placing on the end of the three inch roller a wheel thirty inches in diameter with a band or belt from the two inch pinion to the thirty inch wheel on the top of the frame and opposite to the cylinder is placed one knife in an angular frame for the purpose of shaving all kinds of leather and also a rubber for smoothing leather both of which are moved in the same manner by placing at the two corners of the two corners of the frame two small pulleys six inches diameter each on its own shaft suspended by two posts each with a crank on the inside ends of the shafts. on these cranks is placed a track that extends from and fastened to the one knife and rubber for the purpose of moving them back and forward which by a quicker motion will shave leather placed under them a beam eight inches wide and four

inches thick the rubber on the same manner, the hand, or belly, which first impresses the single knife and roller press over a six inch pulley to and over a thirty inch wheel where a crank is fastened for the purpose of turning the cylinder. The belt for turning the roller under the cylinder passes the thirty inch wheel and placed on the end of the three inch roller under the cylinder and from there to a pulley ten inches diameter by the side of the thirty inch wheel on the end ^{over the top of the one inch shaft} of the one inch shaft placed a roller for the purpose of drawing the leather under the single knife which is moved by a crank placed on the end of one inch shaft which turns the roller that lies on the top and also puts the whole machine in motion. The singular frame in which the single knife is placed may be raised or lowered for the purpose of drawing leather to any desirable thickness by means of screws at the corners of the frame that rise.

For a further illustration of my invention I refer to the model and drawing of the same deposited in the Patent Office. Toyd.
